US0D1050420S

(12) **United States Design Patent** (10) Patent No.: **US D1,050,420 S**
(45) Date of Patent: ** Nov. 5, 2024

(54) **ORAL IRRIGATOR**

(71) Applicants: **Junxiong Feng**, Guangdong (CN); **Xu Deng**, Guangdong (CN)

(72) Inventors: **Junxiong Feng**, Guangdong (CN); **Xu Deng**, Guangdong (CN)

(**) Term: **15 Years**

(21) Appl. No.: **29/891,351**

(22) Filed: **May 4, 2023**

(51) **LOC (14) Cl.** **24-02**

(52) **U.S. Cl.**

(57) **CLAIM**

The ornamental design for an oral irrigator as shown and described.

DESCRIPTION

FIG. 1 is a front, right and top perspective view of an oral irrigator, showing our design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 2; and,

FIG. 10 is an enlarged view of detail 10 in FIG. 7.

The broken lines depict portions of the oral irrigator that form no part of the claimed design.

The dot-dash broken lines in FIGS. 2, 7 9 and 10 depict the boundaries of the enlargements that form no part of the claimed design.

1 Claim, 10 Drawing Sheets
